UNITED STATES PATENT OFFICE.

ALVIN C. GODDARD, OF NEW YORK, N. Y.

FIREPROOF DOOR.

1,295,728.

Specification of Letters Patent. Patented Feb. 25, 1919.

Application filed February 16, 1916, Serial No. 78,598. Renewed January 9, 1919. Serial No. 270,442.

To all whom it may concern:

Be it known that I, ALVIN CARROLL GODDARD, a citizen of the United States, and a resident of the city of New York, Richmond Hill, borough of Queens, in the county of Queens and State of New York, have invented a new and Improved Fireproof Door, of which the following is a full, clear, and exact description.

10 The object of the invention is to provide a new and improved fireproof door which is exceedingly strong and durable in construction, not liable to distortion, and arranged to prevent flames from reaching the 15 interior of the stiles and rails in case of a fire.

In order to produce the desired result, use is made of tubular stiles and rails of sheet metal, each stile or rail having projecting flanges at the inner edge, a panel having its edges spaced from the inner sides of the stiles and rails, and sheet metal panel-attaching members engaging the panels and having extensions projecting beyond the 25 edges of the panel and overlying said covering flanges, the said extensions and covering flanges being welded together. Use is also made of a corner piece covering up the joints of the stiles and rails.

30 A practical embodiment of the invention is represented in the accompanying drawings forming a part of this specification, in which similar characters of reference indicate corresponding parts in all the views.

35 Figure 1 is a sectional perspective view of one corner of the wooden filling or core; Fig. 2 is a similar view of the same with the corner pieces in position on the wooden stile and rail fillings or cores;

40 Fig. 3 is a similar view of the same with the tubular rail in place on the rail filling or core;

45 Fig. 4 is a similar view of the same with the tubular rail and stile in place on the rail or stile filling or core;

Fig. 5 is a cross section of the same on the line 5—5 of Fig. 4.

Fig. 6 is a sectional plan view of the same on the line 6—6 of Fig. 4;

50 Fig. 7 is a perspective view of one end of a rail;

Fig. 8 is a sectional perspective view of one end of a stile; and

Fig. 9 is a perspective view of one of the corner reinforcing pieces.

The door is provided with wooden stile fillings or cores 10 and wooden rail fillings or cores 11 joined together in the usual manner by tongues and grooves 12 but with grooves 13, 14 at the joints, the grooves extending lengthwise of the stile fillings, as plainly indicated in Figs. 1, 2 and 6. Each joint of a stile filling 10 and rail filling 11 is protected at the inner edges thereof by two corner pieces 15 alike in construction and overlying the stile and rail fillings from their opposite faces, as plainly shown in Fig. 2. Each of the corner pieces 15 is made of a single piece of sheet metal stamped to provide side members 16, 17, standing at a right angle one to the other and fitting against the inner edges of the stile and rail fillings. The side members 16 and 17 are provided with an integral offset 18 parallel with the side member 16 and extending into the corresponding groove 13 or 14. The outer ends of the side members 16 and 17 are provided with flanges 19 and 20 overlying the corresponding faces of the stile fillings 10 and rail fillings 11, and the inner ends of the side members 16 and 17 are connected with each other by a connecting flange 21 adapted to abut against the corresponding flange 21 of the other corner piece used at the same corner, it being understood that the flanges 21 meet approximately midway of the thickness of the stile filling 10 and rail filling 11. The two overlying flanges 21 of the two corner pieces are fastened together by rivets, spot welding or other suitable means.

After the two corner pieces are placed in position at each corner of the door filling, the rail filling 11 is covered by a tubular sheet metal rail 25 completely incasing the rail filling but being split at the inner edge of the rail filling and provided thereat with two flanges 26 and 27 extending integrally from the walls of the split in an inward direction. The faces of the rail 25 terminate in inwardly extending offsets 28, 29 fitting into the grooves 13 and 14, and the offsets 28 and 29 terminate in flanges 30 and 31 extending over onto the face of the stile filling 10. The outer edge of the rail 25 is provided with an extension 32 adapted to be folded 100 over onto the end of the stile filling 10,

as will be readily understood by reference to Fig. 3. The flange 27 has its terminal portion 33 slightly offset and the corresponding portion of the other flange 26 is 5 cut out so that the portion 33 overlies the flange 21 of the rear corner piece 15, as plainly shown in Fig. 3. The faces of the rail 25 overlie the flanges 20 of the corner pieces and the flanges 30 and 31 extend over 10 portions of the flanges 19 of the corner pieces 15.

The stile filling 10 is incased in a tubular sheet metal stile 40, split lengthwise at the inner edge and provided along the split with 15 flanges 41 and 42, of which the flange 42 terminates at the outer edge of the flange 27 while the other flange 41 is provided at its end with an offset portion 43 overlying the corresponding flange 21 of the front 20 corner piece 15 (see Fig. 4). The flanges 21 and the offset portions 33 and 43 of the flanges 27 and 41 are fastened together by spot welding or other means. The inner side of the stile 40 is provided with cut-out portions 44 to form flanges 45, 46 to extend into the offsets 28 and 29 of the rail 25. The faces of the stile 40 are provided with extensions 47, 48 and the outer side is provided with an extension 49, the latter being folded 30 over against the end of the stile filling 10, after which the extensions 47 and 48 are folded over the extension 49 (see Fig. 5) to completely incase the end of the stile filling 10. The terminals of the extensions 47 and 35 48 are preferably united by an interlocking seam 50, as plainly indicated in Fig. 5.

It will be noticed that when the stile 40 is placed in position on the stile covering 10 it overlies the flange 30 and the exposed 40 portion of the flange 19 as well as the extension 32 and a comparatively smooth joint is had between the connected stiles and rails.

From the foregoing it will be seen that a fireproof door constructed in the manner 45 described does not present any portions of the wooden stile and rail fillings to flames in case of a fire especially as the joints are securely protected by the corner pieces 15. It will also be noticed that by joining the 50 stiles and rails together in the manner described an exceedingly strong and durable door is provided and one that is not liable to distortion by the shrinking of the wood when the door is subjected to heat in case of 55 conflagration.

Having thus described my invention, I claim as new and desire to secure by Letters Patent:

1. A fireproof door, comprising wooden 60 stile fillings, wooden rail fillings joined with the stile fillings and provided at their ends with grooves, a tubular rail for each rail filling and having offsets and flanges at the ends, the offsets extending into the 65 said grooves and the flanges overlying the

faces of the adjacent stile filling, and a tubular stile inclosing the corresponding stile filling and provided at each end of the inner member with a cut-out portion to form flanges extending into the offsets of the rail. 70

2. A fireproof door, comprising wooden stile fillings, wooden rail fillings joined with the stile fillings, the said stile and rail fillings forming grooves between them at the joints, a tubular rail inclosing each rail filling and 75 having its faces terminating in offsets and flanges, the offsets extending into the said grooves and the flanges overlying the adjacent stile filling, the said tubular rail being split at the inner edge and provided thereat with flanges fastened together, and a tubular stile inclosing the corresponding stile filling and split lengthwise at the inner edge and provided along the split with flanges fastened 80 together by spot welding, the flanges terminating a distance from each end of the stile, each end of the stile being provided with a cut-out portion to form flanges extending into the said offsets of the rail. 85

3. A fireproof door, comprising wooden 90 stile fillings, wooden rail fillings joined with the stile fillings, and provided at their ends with grooves, a tubular rail for each rail filling and having offsets and flanges at the 95 ends, the offsets extending into the said grooves and the flanges overlying the faces of the adjacent stile filling, and a tubular stile inclosing the corresponding stile filling and provided at each end of the inner member with a cut-out portion to form flanges 100 extending into the offsets of the rail, the said stile being provided at each end and on both faces and at the outer edge with integral extensions incasing the end of the stile filling. 105

4. A fireproof door, comprising wooden stile fillings, wooden rail fillings joined with the stile fillings and provided at their ends with grooves, a tubular rail for each rail filling and having offsets and flanges at the 110 ends, the offsets extending into the said grooves and the flanges overlying the faces of the adjacent stile filling, and a tubular stile inclosing the corresponding stile filling and provided at each end of the inner members with a cut-out portion to form flanges 115 extending into the offset of the rail, the said stile being provided at each end and on both faces and at the outer edge with integral extensions incasing the end of the stile filling, 120 the terminals of the face extensions being united by an interlocking seam. 125

5. A fireproof door, comprising wooden stile fillings, wooden rail fillings joined with the stile fillings and provided at their ends 125 with grooves, corner pieces fitting against the adjacent ends of a stile filling and rail filling at the inner edges thereof, each corner piece having an extension fitting against the walls of the corresponding groove, a 130

- tubular rail for each rail filling and having offsets and flanges at the ends, the offsets extending into the grooves and the flanges overlying the faces of the adjacent stile filling, and a tubular stile covering the corresponding stile filling and provided at each end of the inner member with a cut-out portion to form flanges extending into the said offsets of the rail.
- 10 6. A fireproof door, comprising wooden stile fillings, wooden rail fillings joined with the stile fillings and provided at their ends with grooves, corner pieces fitting against the adjacent ends of a stile filling and rail filling at the inner edges thereof, each corner piece having an extension fitting against the walls of the corresponding groove, a tubular rail for each rail filling and having offsets and flanges at the ends, the offsets extending into the grooves and the flanges overlying the faces of the adjacent stile filling, and a tubular stile covering the corresponding stile filling and provided at each end of the inner member with a cut-out portion to form flanges extending into the offset portions of the rail, the said corner pieces having flanges
- 15 and the said tubular stiles and rails having flanges at their inner members, the terminals of the stile and rail flanges overlying the corner piece flanges. 30
7. A fireproof door provided with a corner piece having side members standing at a right angle one to the other and having a U-shaped integral offset parallel with one side member and at a right angle to the other 35 side member.
8. A fireproof door provided with a corner piece having side members standing at a right angle one to the other and having a U-shaped integral offset parallel with one 40 side member and at a right angle to the other side member, the side members having angular flanges at one end and a connecting flange at the other end.
- In testimony whereof I have signed my 45 name to this specification in the presence of two subscribing witnesses.
